UNITED STATES PATENT OFFICE.

GEORGE W. CAMPBELL, OF HARTFORD, CONNECTICUT, ASSIGNOR TO UNDERWOOD
TYPEWRITER COMPANY, OF NEW YORK, N. Y., A CORPORATION OF DELAWARE.

TYPEWRITING MACHINE.

Original application filed February 20, 1922. Serial No. 537,718. Divided and this application filed
March 25, 1924. Serial No. 701,679.

To all whom it may concern:

Be it known that I, GEORGE W. CAMPBELL, a citizen of the United States, residing in Hartford, in the county of Hartford and 5 State of Connecticut, have invented certain new and useful Improvements in Typewriting Machines, of which the following is a specification.

The present invention relates to sound-deadening casings for typewriting machines.

Such a casing usually has a pane of transparent glass through which the operator may observe the printing on the platen. 15 Various expedients have been resorted to for preventing objectionable reflections from the surface of the glass to the eyes of the operator. Blinds have been provided, positionable upon the casing in such manner as 20 to intercept the rays of light directed at said pane.

An object of the present invention is the provision for this purpose of a blind of an improved construction, which may be connected to the casing in a simple manner, and readily detached; and which may be marketed as an article, unitary in itself; and which, to be applied to the casing, requires no modification or special structure of the 30 latter.

This is a division of my co-pending application, Serial No. 537,718, filed February 20, 1922.

Other features and advantages will hereinafter appear.

In the accompanying drawings,

Figure 1 is a fragmentary view, in side elevation, partly cross-sectional, showing the upper part of the casing, the upper part 40 of the typewriting machine being indicated in the casing.

Figure 2 is a cross-sectional detail view, on the line 2-2 of Figure 1, showing the attachment of the blind to the casing-cover.

45 Figure 3 is a front view of the assembly shown in Figure 1 except that the typewriting machine is not indicated.

Referring to the drawings, the sound-deadening casing for the typewriting machine 50 is shown as comprising a body-portion 10, having a cover-part 11 hinged thereto at 12. The casing is preferably a die-casting, having a lining, not shown, of suitable sound-deadening material.

The casing 10-11 has the usual opening 55 41 in the top of the cover 11, through which the operator may observe the printing on the platen. A rectangular ribbing 42, depending inward from the top of the cover 11, serves as a frame for a window-pane 43 60 of glass or other transparent material, and clamps 44 serve to hold the window-pane 43 against a seat 45 in the ribbing 42. Sheet-metal ears 46, secured by screws 47 to the side walls of the window-frame, serve 65 as bearings for pivot pins 48, on which are mounted arms or plates 49 which support a blind 50. The plates 49 are cut away at 51 centrally of their upper edges, and, forward and rearward of these cuts 51, have offsets 70 52, to which the blind 50 is soldered or otherwise secured. The blind 50 may be of thin sheet-metal or other suitable material; and, to strengthen the same, is provided near its edges with corrugations 53, and is centrally 75 curved as at 54.

In Figure 1 the blind 50 is shown as set at such an angle that its rear edge 55 rests upon or is in contact with the top of the cover 11. The angular setting of the blind 80 may, however, be varied at will by loosening the nuts 56 on the screws 48, which serve as the pivot pins for said arms 49, and by tightening these nuts after the arms 49 have been swung to the desired position. 85

It will be noted that, upon removal of the screws 47, the ears 46, together with the arms 49 and blind 50, may be removed as a unit when desired. It will also be noted that the blind 50 and its connections are attached to the cover 11 without modification of the latter, and that the attachment is so simple and convenient that the device may be marketed independently of the casing 10-11, to be bought and attached to the 95 casing if desired.

Variations may be resorted to within the scope of the invention, and portions of the improvements may be used without others.

Having thus described my invention, I 100 claim:

1. A sound-deadening casing for a typewriting machine, having an opening therein through which the operator may observe the printing on the platen of a machine 105 within the same, a frame formed in the wall of the casing for a window-pane, brackets set within the opening and secured to the

sides of the frame, and a blind secured to the brackets.

2. A sound-deadening casing for a type-writing machine, having an opening therein through which the operator may observe the printing on the platen of a machine within the same, a frame formed in the wall of the casing for a window-pane, flat, detachable brackets set within the opening and secured to the sides of the frame, and a blind secured to the brackets.

3. A sound-deadening casing for a type-writing machine, having an opening therein through which the operator may observe the printing on the platen of a machine within the same, a frame formed in the wall of the casing for a window-pane, flat, detachable brackets set within the opening and secured to the sides of the frame, and a blind pivotally adjustable on the brackets.

4. A sound-deadening casing for a type-writing machine, having an opening therein through which the operator may observe the printing on the platen of a machine within the same, a frame formed in the wall of the casing for a window-pane, brackets on the casing, and a corrugated sheet-metal blind secured to the brackets.

5. A sound-deadening casing for a type-writing machine, having an opening therein through which the operator may observe the

printing on the platen of a machine within the same, a frame formed in the wall of the casing for a window-pane, brackets on the casing midway of the sides of the opening, a sheet-metal blind corrugated near its edges, and detachable plates pivotally adjustable on the brackets for supporting the blind midway of the sides thereof.

6. A blind for the window of a sound-deadening casing, comprising a non-transparent plate, arms to which the plate is secured, brackets, and pivotally adjustable connections for the arms to the brackets, such that the brackets, arms and plate form an angularly flexible unitary structure attachable at will to the casing.

7. A sound-deadening casing for a type-writing machine, having therein an opening through which the operator may observe the printing on the platen of the machine within said casing, a frame formed in the wall of the casing for a window-pane, brackets on the casing midway of the sides of said opening, a blind for said pane, and plates pivotally adjustable on the brackets for supporting said blind.

GEORGE W. CAMPBELL.
